George R. Cook, Arlington Heights, Ill., assignor to The
Pure Oil Company, Palatine, Ill., a corporation of Ohio

Filed Aug. 8, 1961, Ser. No. 66,247

Term of patent 14 years

(Cl. D80—11)

FIG. 4

FIGURE 1 is a front perspective view taken from the top and one end of a display cabinet for fire resistant fluids or the like embodying my new design;

FIGURE 2 is a front elevational view thereof;

FIGURE 3 is an elevational view taken from one end thereof; and

FIGURE 4 is a vertical sectional view taken through the line 4—4 of FIGURE 3.

The dominant features of my design reside in the portions shown in full lines.

I claim:

An ornamental design for the display cabinet for fire resistant fluids or the like, as shown and described.
